UNITED STATES PATENT OFFICE.

STANLEY REYNOLDS, OF ROCHESTER, NEW YORK, ASSIGNOR TO THE
STEIN CASKET COMPANY, OF NEW YORK, N. Y.

DESIGN FOR A BURIAL-CASKET.

SPECIFICATION forming part of Design No. 28,615, dated May 10, 1898.

Application filed February 5, 1898. Serial No. 669,275. Term of patent 31 years.

To all whom it may concern:

Be it known that I, STANLEY REYNOLDS, a citizen of the United States, residing at Rochester, Monroe county, State of New York, have invented and produced a new and original Design for Burial-Caskets, of which the following is a specification, reference being had to the accompanying drawings, forming a part thereof.

10 Figures 1 and 2 are perspective views of a burial-casket, showing my design.

The leading feature of the design consists of the ornamental pilaster A, applied to the casket B near the corners thereof, said pilaster having the rounded or convex lower portion a, the ribs or beads b above it, and the narrowed concaved part c, and at the top the two rounded ribs d, the general effect of said ornament being that of a section of an ogee-shaped pillar applied to the corners of the casket.

The casket-body is of the usual oblong shape, with rounded corners, and is ornamented by the two ribs or beadings f g near the lower edge, and also by the rib or bead h below the projecting edge j, and the lid C of the casket has the rounded edge k extending down to the bead or roll l, and below this the inclined surface is extended down to and slightly overhangs the edge j, said surface being broken by the groove n.

25 I claim as my design—

The design for a burial-casket having a pilaster substantially as herein shown and described.

STANLEY REYNOLDS.
